UNITED STATES PATENT OFFICE.

JOSEPH W. BECK, OF JERSEY CITY, NEW JERSEY.

TICKET BOOK.

Application filed November 24, 1928. Serial No. 321,530.

This invention relates to ticket books particularly of the type used in fund-raising campaigns and which comprise a plurality of leaves each comprising a stub portion and a 5 detachable ticket, the various tickets having different inscriptions and the ticket and stub being so connected that the inscriptions of all the tickets are invisible until the ticket is detached.

10 One object of the invention is to provide a novel and improved ticket book of this character wherein the various leaves are firmly secured together and the detachable ticket portion firmly attached to the stub portion 15 so as to avoid accidental detachment of the ticket portions during handling of the book and yet permit easy detachment when such is desired.

Other objects are to provide such a book 20 including a plurality of such leaves and a cover, the leaves being secured together and in the cover in a novel and improved manner; to provide a leaf for such a book embodying novel and improved features of construction 25 and including two spaced permanent stub portions and a ticket portion detachably secured to both said stubs and having an extension arranged between said permanent stubs and detachably secured thereto; to provide a ticket 30 book comprising a plurality of such leaves secured together and in a cover by fastening means passing through all of the permanent stub portions at the end thereof opposite the ticket portion; to provide such a book wherein 35 the fastening means for the leaves consist of four staples, two of which pass through each of the permanent stub portions with one arranged substantially parallel to the transverse end of the stub portion and the other 40 substantially parallel to the ticket extension, and to obtain other advantages and results as will be brought out by the following description.

Referring to the accompanying drawings, 45 in which corresponding and like parts are designated throughout the several views by the same reference characters,

Figure 1 is a plan view of a ticket book embodying my invention;

50 Figure 2 is a similar view showing the cover folded back to admit of the tickets being removed from the book, and

Figure 3 is a composite view showing the manner of removal of one of the tickets which 55 is shown as being the last ticket in the book.

Specifically describing the illustrated em-

bodiment of the invention, each leaf of the book comprises a ticket portion 1 upon which may be printed suitable inscriptions or descriptive matter 2 indicating the character 60 and purpose of the ticket, said ticket portion being integral with two stub portions 3 and 4 and an extension 5 which projects from one end of the ticket portion on the longitudinal median line thereof and is arranged between said stub 65 portions. For the purpose of enabling detachment of the ticket portion from the stub portion, the leaf may be scored as at 6 and 7. At the extreme end of the ticket extension 5 opposite the ticket 1 is provided a suitable in- 70 scription 8, such as the price at which the ticket is to be sold.

A plurality of the leaves are arranged in superposed relation and secured together at the ends opposite the ticket portions 1 by any suitable means passing through the stub portions 3 and 4. As shown, the fastening means comprise two pairs of staples 9, 10 and 11, 12, and one of each pair of staples, in the present instance the staples 9 and 11, are arranged sub- 75 substantially parallel to the transverse ends of the leaves, while the other staples 10 and 12 of each pair are arranged substantially parallel to the ticket extension 5.

For the purpose of normally hiding or cov- 80 ering the inscription 8, the leaves have preferably secured thereto a cover 13, and the same staples 9, 10, 11 and 12 may be utilized for securing the cover to the book of leaves. With this construction it will be observed that 90 each ticket portion 1 may be separated or detached from its corresponding stub portions 3 and 4 by a firm pull upon the free end of the ticket portion at the point 14, as by gripping the leaf between the thumb and 95 forefinger. When such a pull is exerted, the ticket portion is separated from the stub portions along the lines of scoring 6 and 7, and the ticket extension 5 is thus pulled from beneath the cover portion and the inscription 8 100 thereby made visible. The cover continues to overlie and obscure the inscription 8 on the uppermost remaining leaf.

It will be observed that the strain imposed upon the scored lines 6 are resisted by the 105 staples 9 and 11, while the strain on the scored lines 7 are resisted by the staples 10 and 12. The ticket extension 5 is free from the staples throughout its length and thus can be easily pulled outwardly after the ticket portion is 110 detached along the scored lines. It will also be noted that the ticket portion is at all times

firmly secured to the stub portions against accidental detachment, and the stub portions are firmly secured together and to the cover by the staples.

- 5   The two stub portions 3 and 4 may be utilized for any suitable purpose, for example the stub portion 3 may be adapted to receive the name of the purchaser of the corresponding ticket portion 1, while the stub portion 4
- 10   may be used to receive the name of the salesman or person to whom a vote is to be given, or for any other desired purpose. The construction enables a ticket to be withdrawn from any part of the book, and all of the stubs are retained after all of the tickets have been withdrawn.

To further reenforce the book, the cover is preferably in one piece, having the top portion 13 and bottom portion 16, which receive the leaves between them.

Having thus described the invention, what I claim is:

1. A ticket book comprising a plurality of superposed leaves each including a pair of spaced stub portions at one end and a ticket portion at the other end having an extension disposed between said stub portions and bearing an inscription, said ticket portion and its extension being detachably connected to said stub portions, a cover for said leaves, and means for securing said cover to said leaves and said leaves together with a portion of said cover permanently overlying and obscuring from view said inscription on said ticket extension, whereby said ticket extension will be pulled from beneath said cover when the ticket is detached.

2. A ticket book comprising a plurality of superposed leaves each being divided by scored lines into a pair of spaced stub portions at one end and a ticket portion at the other end having an extension disposed between said stub portions, said ticket portion and its said extension being detachable from both said stub portions along said scored lines, and means for securing said leaves together with said ticket portion and its extension detachable from said stub portions,

whereby a pull upon the end of the ticket portion opposite said stub portions will detach 50 the ticket.

3. A ticket book comprising a plurality of superposed leaves each being divided by scored lines into a pair of spaced stub portions at one end and a ticket portion at the other 55 end having an extension disposed between said stub portions, said ticket portion and its said extension being detachable from both said stub portions along said scored lines, a staple passing through each of said stub portions in a plane parallel to the transverse ends of said stub portions, and other staples each passing through said stub portions in planes parallel and adjacent the scored lines between 60 said ticket extension and said stub portions. 65

4. A ticket book comprising a plurality of leaves each comprising a ticket portion having an integral narrow extension at one end on substantially its longitudinal median line, a pair of stub portions one at each side 70 of said extension, said ticket portion and its said extension being detachably connected to said stub portions, and means for securing all of said stub portions together.

5. A ticket book comprising a plurality of 75 leaves each comprising a ticket portion having an integral narrow extension at one end on substantially its longitudinal median line, a pair of stub portions one at each side of 80 said extension, said ticket portion and its said extension being detachably connected to said stub portions, said extension bearing at its end opposite the body of the ticket portion an inscription, a cover permanently overlying said end of the extension to obscure said 85 inscription, and means for securing said stub portions of each of said leaves to the corresponding stub portions of the other leaves in superposed book form and for securing said cover to said stub portions, whereby said 90 ticket portion can be pulled from beneath said cover to expose said inscription as the ticket portion is detached from said stub portions.
